HOLDER FOR A MEMORANDUM PAD OR THE LIKE

Thomas Francis Nalley, Jr., Crestline, Ohio
Application July 2, 1957, Serial No. 46,816

Term of patent 14 years

(Cl. D74—1)

FIG. 1

FIG. 3

Fig. 1 is a front elevational view of a holder for a memorandum pad or the like showing my new design;

Fig. 2 is a side elevational view; and

Fig. 3 is a sectional view thereof taken on line 3—3 of Fig. 1.

The undisclosed back is plain and unornamented. The essential features of the design reside in the portions shown in solid lines on the drawing and the broken line illustrations in Fig. 3 of a pad and the end of a pencil are for illustrative purposes only.

I claim:

The ornamental design for a holder for a memorandum pad or the like, substantially as shown and described.
